ATTORNEY

WITNESS:

UNITED STATES PATENT OFFICE.

JAMES CARAFILIDIS, OF SABRATON, WEST VIRGINIA.

SMOKER'S PIPE.

Application filed October 30, 1920. Serial No. 420,706.

To all whom it may concern:

Be it known that I, JAMES CARAFILIDIS, a citizen of the United States, residing at Sabraton, State of West Virginia, have invented new and useful Improvements in Smokers' Pipes, of which the following is a specification.

This invention relates to smoking devices, and more particularly to a device which may be used either as a pipe or as a cigar or cigarette holder.

One of the main objects of the invention is to provide a device of the character stated of simple construction and operation which may be produced at small cost. A further object is to provide a device in which the smoke may be drawn through water or other suitable liquid so as to be filtered and cooled thereby. Another object is to provide a device which may be used either as a pipe or as a cigar or cigarette holder. Further objects will appear from the detailed description.

In the drawings:

Figure 1 is a side view of a device constructed in accordance with my invention.

Figure 2 is a longitudinal sectional view through the device.

Figures 3, 4 and 5 are central vertical sections through different types of bowls.

Figure 6 is a detail of a perforated disc to be used in one of the bowls.

The device includes a body 1 of substantially rectangular shape provided at one end with a mouth piece or bit 2. The body is provided at its other end with an upwardly directed neck 3 in the upper end of which is formed a bore 4 adapted to receive a neck 5 formed on the lower end of a bowl 6. The bowl illustrated in Figure 1 is intended to hold tobacco in the ordinary manner of a smoker's pipe, and this bowl may be provided with a perforated disc 8 such as illustrated in Figures 3 and 6. A smoke passage 9 extends from the inner end of

bore 4 and communicates with the forward end of a chamber or reservoir 10 of substantially elliptical shape, and a smoke passage 11 of substantially elongated U-shape is provided in the upper portion of body 1 ⁵⁰ and establishes communication between bit 2 and the rearward end of reservoir 10. In practice a suitable quantity of water or other suitable liquid may be poured into reservoir 10 through passage 9, and this ⁵⁵ water acts to filter and cool smoke which is drawn through it. As will be understood, it is not necessary to place water or other liquid in the reservoir or chamber 10. In this case, this chamber would act as an expansion space for the smoke and would serve to cool and clean the same, the expanded smoke then passing through smoke passage 11.

By providing suitable bowls, this device ⁶⁵ may be adapted for smoking tobacco in its ordinary form, or for smoking cigars or cigarettes. For this purpose I provide the bowls illustrated in Figures 4 and 5. The bowl illustrated in Figure 4 is adapted to receive the end portion of a cigar, that illustrated in Figure 5 being adapted for reception of a cigarette.

What I claim is:—

In a device of the character described, a ⁷⁵ body of substantially elongated rectangular shape provided at one end with a neck and at the other end with a bit, the body being hollowed out to provide a relatively large elongated chamber, said neck being adapted ⁸⁰ for reception of a bowl and communicating with the chamber at the forward end thereof, said body being further provided with an outlet passage of elongated U-shape above the chamber, said passage communicating at one end with the chamber at the rear thereof and at its other end with the bit.

In testimony whereof I affix my signature.

JAMES CARAFILIDIS.
